UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

PLATE-PRINTING MACHINE.

1,288,710.

Specification of Letters Patent. Patented Dec. 24, 1918.

Application filed March 15, 1917. Serial No. 154,962.

To all whom it may concern:

Be it known that I, EDWARD P. SHELDON, a citizen of the United States, residing at New York city, county of Kings, and State 5 of New York, have invented certain new and useful Improvements in Plate-Printing Machines, fully described and represented in the following specification and the accompanying drawings, forming a part of the 10 same.

This invention relates to certain improvements in plate printing machines.

In plate printing machines, the printing is done from a flat engraved plate by means of 15 depressed lines. This plate has to be inked, wiped and polished, and then the impression made on the sheet to be printed therefrom. Usually these steps are effected by giving the 20 plate a rectangular movement in which it is successively passed through inking, wiping and polishing mechanisms and then brought into position to make the impression. In these machines, the impression is effected by means of an impression roll, ordinarily 25 known in the plate printing art as a D-roll, the plate and paper being carried between this roll, which is continuously driven, and a coöperating abutment, usually another roll. In these machines, the sheet is fed to the 30 plate after it has been inked and polished, by an operator who places a sheet on the plate and registers it against a line while the plate is traveling up to the impression or D-roll, this line registration being necessary on 35 account of the construction of the machine, there being no room for front stops, as the machines are ordinarily constructed, on account of the plate having to pass under the D-roll and between it and the abutment.

40 This "line" registration requires great care and accuracy on the part of the operator, and the difficulty is increased by the operator having to perform the registering act while the plate is in motion. Where, as is 45 very often the case, a sheet is to be given an impression in two or more colors, there is great difficulty, in spite of the most careful attention, in getting the sheet properly registered to the line so that the successive colors will be printed in proper register. Furthermore, assuming the sheet to be properly 50 registered to line, there is, in this type of machine, no positive control of the sheet after registration and until it passes into the 55 bite of the D-roll.

It is the object of the present invention to provide a registering device for machines of this type by which the operator can accurately register the sheet and insure perfect registry thereof through two or more impressions, the registering devices being moved out of the way as the plate moves up to the impression or D-roll. 60

It is a further object of the invention to provide a means for holding the sheet in 65 registered position until after the sheet has entered the bite of the impression roll, the sheet holding or controlling devices being then moved out of the way.

It is a further object of the invention to 70 provide a simple and efficient combination of parts for effecting these results.

For a full understanding of the invention, reference may be had to the accompanying drawings, in which— 75

Figure 1 is a side view of so much of a plate printing machine of the type referred to as is necessary for an understanding of the invention, the view showing a plate moving up to the impression roll and the registering devices in operative position; 80

Fig. 2 is a plan view of the construction shown in Fig. 1, certain parts being broken away to more clearly illustrate the invention, showing the sheet is registered position; 85

Fig. 3 is a detail side view showing the mechanism for controlling the registered sheet until it has entered the bite of the impression roll, the registering devices having 90 been moved out of the way, and

Fig. 4 is a detail view, partly in section, showing a convenient sheet controlling mechanism.

Referring now to these drawings, the machine chosen to illustrate the invention is a plate printing machine in which the parts are given a rectangular movement to effect the inking, wiping and polishing, the drawings, however, showing only so much of a 95 machine as relates to the impression or printing of the sheet, although it will be understood that the invention may be and is intended to be used in other types of plate printing machines. As illustrated, the various parts of the machine are mounted in a suitable frame 1, which may be of any usual or desired configuration, this frame being formed with tracks 2 about which moves a plate carrier 3 on which is supported a print- 100 105 110

ing plate 4, the plate being secured to the carrier in any suitable manner, as by clamps 5. This carrier is driven in any suitable manner, as from a continuous chain 6 operated from sprockets 7, only one of which is shown, driven in any suitable manner, as from power shaft 8 through a gear 9 mounted on a shaft 10 and gears 11, 12 operating to drive vertical shafts 13 from which run 10 suitable driving connections to the carrier.

The impression or printing of the sheet is effected by causing the plate carrier to pass between an impression or D-roll 14 and a co-operating abutment which, in the present instance, is a roll 15. The impression or D-roll is a continuously driven roll, as is usual, being driven in any suitable manner as by an endless chain 16 passing over a sprocket secured on the end of the roll beyond the 20 side frame and a sprocket 17 on the shaft 10, before referred to, the usual means, such as roll 18, being provided for keeping the chain 16 under suitable tension. The impression or D-roll is, as is usual in these machines, a 25 blanketed roll, and is mounted in spring seated bearings for providing a yielding impression, one of the springs being indicated at 19.

Machines constructed in accordance with 30 the invention will be provided with registering devices for registering the sheet on the plate as it moves up to the impression or D-roll, these registering devices being moved out of the way to permit the plate and plate 35 carrier to move between the D-roll and the co-operating abutment. While these devices may be of various characters and operated in various ways, they will be of such character as to be brought into registering position as 40 the plate and plate carrier advances toward the impression roll, moving with the plate and plate carrier for a sufficient time to permit the operator to register the sheet and then moving out of the way. In the particular 45 construction illustrated, there are provided a pair of these registering devices in the form of stops, one of which is shown in Figs. 2 and 3, marked 20, located so as to be brought into position at each side of the 50 plate. These stops may be of various configuration, but in the particular construction shown are formed with two sides 21, 22 arranged at right angles to each other, as shown in Fig. 2, thus providing an effective 55 guide and stop for accurately positioning the sheet.

These registering stops are, as before stated, moved out of the way when the plate carrier and plate are about to enter the bite 60 of the impression roll. While this may be effected in various ways, the stops are, both for this purpose and for permitting them to advance with the plate, mounted on a traveling carrier which acts to advance the stops 65 until just before the plate enters the bite of

the impression roll. This carrier may, of course, vary widely in construction, but a simple and convenient one is that illustrated in which is provided a pair of chains 23, 24 at each side of the plate path, these 70 chains being, as shown in Fig. 1, mounted so as to give the stops a considerable advancing movement with the plate and then a quick movement out of the way. In the particular construction illustrated, the 75 chains are mounted on sprockets 25, 26, 27 carried on shafts 28, 29, 30, respectively, suitably mounted in adjustable bearings 31 in brackets 32 secured to the frame of the machine, the sprockets being preferably arranged substantially triangularly, as shown. With this arrangement, referring to Fig. 1, the stops are given an advancing movement 80 along the base of the triangle in operative relation with the plate and a quick removal 85 out of the way as the plate is about to enter the bite of the impression roll. The carrier, where the carrier includes chains and sprockets, may be driven from the impression roll through a gear 33 mounted on the 90 shaft 34 thereof through an intermediate 35 and a gear 36 mounted on one of the sprocket shafts before referred to, this gear in the particular construction illustrated being mounted on the shaft 28, the gears being so 95 proportioned that the carrier chains have a movement substantially that of the plate carrier.

In machines embodying the invention in its best form means will be provided whereby 100 after the sheet is registered it will be positively held in registered position after the stops have been withdrawn and until the sheet has entered the bite of the impression roll. While these means may, of course, be 105 varied in construction, where the stop carrier is a pair of chains these controlling means may be carried on the chains, being arranged thereon a sufficient distance from the stops to come into operation after the 110 sheet has been registered against the stops. These sheet controlling devices are marked 37 and are, as illustrated (Figs. 1 and 3), carried on the carrier chains 23 and 24, before referred to. While the particular construction of these sheet controlling devices may be varied, as illustrated they are in the form of fingers 38 secured in brackets 39 carried by the chains, the fingers being secured in the brackets by means of pins 40 115 adapted to work in slots 41, the fingers being yieldingly held against the sheet by means of springs 42 disposed in the sockets.

With the construction described, it will be seen that as the plate carrier is moved up to 120 the impression roll the stops 20 are brought into operative relation with the plate carrier and moved along therewith at substantially the speed of the carrier, giving the operator 125 time to accurately register the sheet against 130

the stops. As the carrier advances, the stops advance with it, and as the plate carrier enters the bite of the impression roll, the stops are, due to the arrangement, quickly withdrawn out of the way. As the carrier advances, after the sheet has been registered, the controlling fingers 37 are brought into position and these controlling fingers 37 hold the sheet in registered position until after 10 the plate carrier has advanced so that the sheet has entered the bite of the impression roll, as shown in Fig. 3, the fingers being then lifted out of the way by the continuing movement of the chains. A simple and effective mechanism is, therefore, provided, both for registering the sheet and holding it in registered position until it is positively taken by the rolls.

While the invention has been shown and 20 described in a preferred form, it will be understood that various changes may be made, both in the construction of the stop carrier and in the particular form of stops and controlling devices, and that the invention is not 25 to be restricted to the precise details of construction illustrated and described.

What is claimed is:

1. In a plate printing machine, the combination with a plate carrier and means for 30 continuously advancing it, of an impression cylinder and coöperating abutment between which the plate carrier passes, means independent of the plate carrier for effecting the registration of a sheet carried thereby, and 35 means for withdrawing the sheet registering means out of the path of movement of the plate carrier.

2. In a plate printing machine, the combination with a plate carrier and means for 40 advancing it, of an impression cylinder and coöperating abutment between which the plate carrier passes, a stop carrier independent of the plate carrier, stops carried thereby for effecting the registration of a 45 sheet carried by the plate carrier, and means for operating the stop carrier to withdraw the stops out of the path of movement of the plate carrier.

3. In a plate printing machine, the combination with a plate carrier and means for 50 advancing it, of an impression cylinder and coöperating abutment between which the plate carrier passes, a stop carrier, stops carried thereby for effecting the registration of a 55 sheet carried by the plate carrier, and means for operating the stop carrier to cause the stops to advance with the plate carrier and be withdrawn from the path of movement thereof when the plate carrier reaches the 60 impression cylinder.

4. In a plate printing machine, the combination with a plate carrier and means for 65 advancing it, of an impression cylinder and coöperating abutment between which the plate carrier passes, a pair of chains, stops

carried by the chains, sprockets over which the chains pass arranged substantially triangularly, and means for driving the chains whereby the stops are advanced with the plate carrier and are withdrawn from the 70 path of movement thereof as it approaches the impression cylinder.

5. In a plate printing machine, the combination with a plate carrier and means for advancing it, of an impression cylinder and 75 coöperating abutment between which the plate carrier passes, means advancing with the plate carrier for effecting the registration of a sheet carried thereby, means for withdrawing the sheet registering means 80 out of the path of movement of the carrier as it reaches the impression cylinder, and means for positively controlling the sheet after registration by the stops and until the sheet enters the bite of the impression 85 cylinder.

6. In a plate printing machine, the combination with a plate carrier and means for advancing it, of an impression cylinder and coöperating abutment between which the 90 plate carrier passes, means advancing with the carrier for effecting the registration of a sheet carried thereby, means for withdrawing the sheet registering means out of the path of movement of the carrier as it reaches 95 the impression cylinder, means for positively controlling the sheet after registration by the stops and until the sheet enters the bite of the impression cylinder, and means for then withdrawing the sheet controlling 100 means out of the path of the movement of the carrier.

7. In a plate printing machine, the combination with a plate carrier and means for advancing it, of an impression cylinder and 105 coöperating abutment between which the plate carrier passes, a stop carrier, stops carried thereby for effecting the registration of a 110 sheet on the carrier, means for operating the carrier to withdraw the stops out of the path of movement of the carrier, and sheet controlling means mounted on the carrier and controlling the sheet until it is taken by the impression cylinder.

8. In a plate printing machine, the combination with a plate carrier and means for advancing it, of an impression cylinder and coöperating abutment between which the plate carrier passes, a stop carrier, stops on 115 the carrier for effecting registration of the sheet carried by the plate carrier, sheet controlling fingers mounted on the carrier behind the stops, and means for operating the carrier to successively bring the stops and the controlling fingers into operative relation with the carrier and to remove them from out of the path of movement of the carrier as it reaches and passes into the bite of the impression roll.

9. In a plate printing machine, the com- 130

bination with a plate carrier and means for advancing it, of an impression cylinder and coöperating abutment between which the plate carrier passes, a pair of chains, registering stops mounted on the chains, sheet controlling fingers mounted on the chains, means for driving the chains to bring the stops and the controlling fingers successively into operative relation with the plate carrier and for successively removing them out of the path of movement of the carrier as it reaches and passes into the bite of the impression cylinder.

10. In a plate printing machine, the combination with a plate carrier and means for advancing it, of an impression cylinder and coöperating abutment between which the plate carrier passes, a pair of chains, sprockets over which the chains pass arranged 20 triangularly with respect to each other whereby the chains may be given a right line movement parallel with the movement of the plate carrier, registering stops carried by the chains, sheet controlling fingers carried by the chains, and means for driving one of the sprockets to cause the chains to advance the stops and fingers successively in coöperative relation with the plate carrier and successively remove the stops and 30 fingers as the carrier reaches and passes into the bite of the impression cylinder.

11. In a plate printing machine, the combination with a plate carrier and means for advancing it, of endless carrier chains arranged 35 above the plate carrier path, angular registering stops carried by the chains and arranged to move with the plate carrier, means for driving the chains to lift the stops out of the plate carrier path, and 40 impression means.

12. In a plate printing machine, the combination with a plate carrier and means for advancing it, of endless carrier chains arranged 45 above the plate carrier path, registering stops carried by the chains and arranged to move with the plate carrier, spring controlling fingers carried by the chains and moving with the plate carrier, means for driving the chains to lift the 50 stops and fingers successively out of the plate carrier path, and impression means.

13. In a plate printing machine, the combination with a plate carrier and means for advancing it, of an impression cylinder and 55 coöperating abutment between which the plate carrier passes, means for effecting the front registration of a sheet carried on the

carrier, means for positively controlling the sheet after registration and until the sheet has entered the bite of the impression cylinder, and means for removing the sheet controlling means out of the path of movement of the carrier. 60

14. In a plate printing machine, the combination with a plate carrier and means for advancing it, of an impression cylinder and coöperating abutment between which the plate carrier passes, means for effecting the front registration of the sheet carried by the carrier, a pair of chains, controlling fingers 70 carried by the chains for positively controlling the sheet after registration and until it is taken by the impression cylinder, and means for driving the chains to remove the controlling fingers out of the path of movement of a plate carrier after the sheet has been taken by the impression cylinder. 75

15. In a plate printing machine the combination of a plate carrier and coöperating impression means, of means for advancing 80 the carrier, registering stops independent of the carrier, and means for withdrawing the stops from the path of the advancing carrier.

16. In a plate printing machine the combination of a plate carrier and coöperating 85 impression means, of means for advancing the carrier, registering stops independent of the carrier, means for positively controlling the sheet after registration by the stops, and means for moving the registering stops and 90 the controlling means out of the path of the advancing carrier.

17. In a plate printing machine the combination of a plate carrier and means for advancing it, of endless flexible carriers arranged 95 above the plate carrier path, registering stops carried by the carriers and movable forward therewith, means for driving the endless carriers to move the stops out of the plate carrier path, and impression means. 100

18. In a plate printing machine the combination of a plate carrier and means for advancing it, of endless flexible carriers arranged above the plate carrier path, registering stops and controlling fingers carried by 105 the carriers, means for driving the endless carriers to advance them with the plate carrier and to move the stops and fingers out of the plate carrier path, and impression means.

In testimony whereof, I have hereunto set my hand.

EDWARD P. SHELDON.
